UNITED STATES PATENT OFFICE

ARTHUR L. BLAKEMORE, OF CHICAGO HEIGHTS, ILLINOIS, ASSIGNOR TO AMERICAN MANGANESE STEEL COMPANY, OF CHICAGO, ILLINOIS, A CORPORATION OF MAINE
METHOD OF AND MEANS FOR BALANCING ROTARY BODIES HAVING RADIATING BLADES

Application filed June 8, 1928. Serial No. 283,787.

This invention relates to bodies, which, because of the high rates of speed at which they rotate in service it becomes important to have them accurately balanced about their centers of rotation; and particularly bodies 5 into the construction of which blade-like members enter.

It has long been proposed in the manufacture of rotary bodies, notably crank shafts 10 for automobiles and other machinery where accurate balancing is important, to forge the blanks from which the crank axles are made with substantial masses of metal upon those portions of the crank arms or cheeks lying 15 on the opposite side of the center of rotation from the wrists of the crank, and to place the crank when substantially completed in a testing machine adapted to indicate imbalance relatively to the center of rotation of the 20 entire mass that enters into the piece, the excess of metal provided on the opposite side of the center from the cranks being gradually removed by grinding, drilling, or other convenient method until satisfactory balance 25 is attained. It has also been proposed to apply to the rear surfaces of the blades of a rotor in a rotary pump, so-called coupons or fins of metal extending transversely of the blades in lines parallel with the axis of rotation, and adapted by the removal of one or 30 more of the coupons to bring the center of mass into coincidence with the center of rotation.

Now, the object of the present invention is 35 to provide an improved method of and means for balancing rotors of pumps, namely, a method and means that will avoid obstruction to radial flow of material entering between the blades, will strengthen the outer 40 portion of the blade in a plane or planes radial to the axis of rotation as well as normal thereto, and, by reason of the range of distance from the center through which the strengthening means extends and consequent 45 range of leverage with which different points in the strengthening fin will act, will permit of a very much more gradual and refined adjustment of mass than when it became necessary to remove metal from individual fins 50 extending transversely and therefore lying

wholly at definite distances from the center.

In the accompanying drawing—

Figure 1 is a side elevation of a rotor of standard design in which the present invention is embodied, those portions of the blades 55 which carry the balancing fins and which are obscured by the annular wall of the rotor, being shown in dotted lines.

Figure 2 is a section on the line 2^x—2^x of Figure 1; and

Figure 3 is a view similar to Figure 2 showing a modification of the balancing fin.

1 represents a hub, 2 blades, 3 an annular wall surrounding eye 4 of the rotor and formed integrally with the blades 2 upon one 65 side, and 5 represents a disk or circular wall formed integrally with the blades 2 on the other side.

In order to balance the integral piece constituting the rotor and identified by the 70 numerals 1 to 5, each blade 2 has cast integrally with its rear surface one or more fins 6 (Figures 1 and 2 where the fins terminate short of the radial extremity of the blades) or 6^a (Figure 3 where the fin extends completely to the periphery), so that within the 75 limits of their radial dimensions they provide continuous masses of metal at gradually increasing distance from the center of rotation, from which metal can be removed by 80 any convenient method, preferably grinding or burning torch, when as is usual the rotor is made of cast manganese steel. Not only do the fins 6 afford radially continuing surfaces from which to remove excess metal in 85 balancing the rotor, and thereby admit of a more gradual and more refined balancing, for instance, by applying the reduction process continually along a radial surface and therefore at varying distances from the center of revolution, according to the fineness of balance required, but said fins constitute 90 strengthening elements for the backs of the blades and they occupy positions which do not obstruct sand, gravel, or other solids flowing in through the eye 4 and outward between the blades of the rotor under the suction of the pump; or produce cupping or 95 eddy currents that interfere with the free flow of material being pumped; or consti- 100

tute energy absorbing element, as is the case where coupons or transverse flanges are used. Still another advantage arising from the incorporation of radially disposed fins into the structure of blades such as 2, that are cast integrally as webs between two spaced walls such as 3 and 5, is that in the process of cooling the web-like portion of the casting can draw fluid metal from the fins and prevent the formation of cooling cracks, metal voids, etc.

10 I claim:

1. A pump rotor embodying in its construction blades arranged around an axis of rotation, and having upon said blades, fins 15 adapted to be individually reduced in mass for balancing the mass of the rotor upon its axis of rotation; the fin upon each blade being in a plane perpendicular to the axis of rotation and of reduced dimension in the 20 direction of the width of the blade, and leaving on the sides of the fin free and unobstructed space for the flow of material impelled by the pump.

2. A rotary pump impeller, comprising 25 blades and balancing fins on said blades; there being a plurality of such fins on a blade arranged in substantially parallel planes perpendicular to the axis of rotation of the impeller, with spaces between and on 30 the outer sides of said fins for the free flow of material pumped; said fins being adapted to be reduced in mass for balancing the impeller upon its axis of rotation.

Signed at Chicago Heights, Illinois, this 35 twenty-eighth day of May, 1928.

ARTHUR L. BLAKEMORE.
